UNITED STATES PATENT OFFICE

2,539,878

CLAPPER BLOCK

John M. Walter, Cincinnati, Ohio, assignor to The
G. A. Gray Company, Cincinnati, Ohio, a cor-
poration of Ohio

Application May 2, 1947, Serial No. 745,518

8 Claims. (Cl. 90—55)

1

My invention relates to devices used in metal planers on which the tools are supported that cut into the work as the latter traverses past them. In the usual construction in planers a tool box is provided which is supported so as to be tiltably adjustable, this box serving to mount the apron or the clapper block in a pivotal manner between two side bars which form a pocket in which the block lies when in operating position. The tool box is mounted on a slide supported on the harp of the machine, which slide may be moved up and down on the saddle either by power or by hand.

In the operation of a planer, the tools cut into the work normally while it is moving in one direction, and are idle when the work moves in the opposite direction. It is for this reason that the block or apron which holds the tools is pivotally mounted at its upper end, so that the tools can trail over the surface of the work on its return movement. It is desirable, however, and modern planers are so equipped, to provide means for lifting the apron slightly by an automatically operating device such that when the work stroke of the planer table is completed the apron or clapper block will be pushed off its seat ready to trail the tools over the work.

Carrying this idea further it has been suggested that means be provided for imparting a higher lift to the apron, to the end that the tools are lifted clear of the work and will not drag over it. It is to the end of providing a practical device to accomplish this purpose that the present invention is directed. As illustrated, the invention is shown as applied to a particular spring counterbalanced apron of my pending application for Patent Ser. No. 713,325, filed November 30, 1946, and now Patent No. 2,530,343, granted November 14, 1950, and as utilizing a standard type of mechanism of lifting pin for the apron, which the objective of my invention is to augment, rather than seeking to provide an entirely different mechanism. In many of its aspects my invention can be applied to various lifting devices, and the spring counterbalanced type of apron, while desirable as a combination element in my invention is not essential. It will be realized from the above statement that a lifting device for the apron must be one which can operate irrespective of the position of the tool box on its slide or of its slide on the planer saddle. Such a device is inherently confined in its amplitude of movement because of the necessities of construction, whereby it is fitted in with the necessary elements of the saddle, slide, and tool box. It may

2

be stated that irrespective of the particular mechanism used to operate it, the usual lifter for planer aprons consists of a slide pin mounted in the tool box and operated from mechanism controlled from the planer rail, with a short range of movement.

The drawings are illustrative of an example of my invention and should not be taken as disclosing the only available mechanical instrumentalities to which my invention may be applied.

In the drawings:

Figure 1 is a side elevation of part of the slide, the tool box and apron according to my invention.

15 Figure 2 is a front elevation thereof.

Figure 3 is a front elevation of the tool box, with the apron removed from its mounting.

20 Figure 4 is a vertical section taken through the rail saddle, slide, box and apron showing the novel parts therein incorporated according to my invention.

25 Figure 5 is a view illustrating the angle of lift attained by my device, being a section on the scale of Figure 4 but omitting the operating parts for the lift.

Figure 6 is a perspective of the augmenting plate.

Figure 7 is a detail of the operating end of the rock plate operating device in perspective.

Figure 8 is a detail perspective showing the mounting for the rock plate.

Referring first to the general parts illustrated the cross rail of a planer is indicated at 1, the saddle at 2, the slide on which the tool box is supported at 3, and the tool box at 4. The apron 5 is hinged on a pin 6 supported at the upper end of the two side bars 7 of the tool box. In this case a fixed thimble 8 secured over one end of the pin 6, mounts a torsional spring 9 which has a free end bearing on a projection of the mounting bar 10 of the apron. This is the structure of my co-pending application above identified to which reference is hereby made for further details and principles of the structure. The spring 9 tends to lift the apron, thus serving as a counterbalance for its gravity movement to position against the face of the tool box between the two side bars thereof. I have indicated a cutting tool 11, secured by the nuts on bolts 12, there being cross bars 13 on the bolts which advance and clamp the tools in position (see Fig. 4), on the apron.

55 The tool box swivels on a bushing 14 located in the lower portion of the slide 3, being held in adjusted position by bolt heads on the bolts 15 located in the slide; said bolts passing through the usual arcuate slot 16 of the tool box.

Secured on the inner face of the slide in a hollow space adapted for the purpose are a pair of lugs 17, 17, and a rock plate 18 is provided extending between the two lugs and having slotted ends 19 (Fig. 8), which engage over the lugs and are held in place by suitable pivot pins passing through the slotted ends and the lugs.

This plate when rocked will engage a pin 20, which is the lift pin of the device, which is spring pressed toward the rock plate, and slidably held in the bushing 14. The spring pressure is adjusted by a threaded nipple 21 in the outer end of the bushing 14. When the plate is rocked the pin will be pressed outwardly through the bushing and thus supply the power for lifting the apron from its operating seat. As shown, the apron has an overhanging lip 22 which engages under the shoulder at the lower edge of the tool box, to give firm support for the apron. The apron must naturally also move away from this shoulder when lifted.

Going back from the rock plate, the mode of operating it which is shown for illustrative purposes, is a rod 23 having a widened and slotted outer end 24 which rides over the elevating screw 24a for the slide. This outer end is provided with a pin 25 (Fig. 7), which bears against the rock plate so that when the rod is reciprocated the plate is rocked, contact being maintained by the spring on the push pin.

The rod 23 is introduced into the space occupied by the feed screw by passing through the drive sleeve 26 for the screw. This sleeve has a beveled gear 27 cut on its inner end which meshes with a bevel gear on a collar 28 which rotates the feed screw when it is driven by power.

As so far described there is no substantial difference in the mechanism than that already in use prior to my present invention or which is shown in my co-pending application.

A cavity is formed in the back face of the apron as shown at 29, this cavity being of a shape to clear the motion increasing tongue 30 which is hinged at 31 to the shoulder at the lower end of the tool box. When the apron is in normal operating position the tongue lies within this cavity as well as the hinged mounting for the tongue.

The tongue lies in front of the push pin, at a location selected with reference to the pivot point and length of the tongue so that the result of pushing in on the push pin will be to rock the tongue on its hinge a selected distance. The upper end of the tongue will bear on the wall of the clearance cavity in the back of the apron resulting in a lifting motion which is considerably greater on the apron, than would be the movement of the pin itself.

This motion increaser results in giving the added elevation of the apron which is desired lifting the tools on the apron well away from the surface of the work during its return strokes.

I have indicated a rocker 32 which moves the rod 23, this rocker located in the rail of the planer, and put into motion upon reversal of the table movement.

It will be evident that the motion increaser located as it is permits of the use of any regular push pin mechanism on a planer and that the amount of motion of the apron is governed by the length of the tongue, and the proximity of the push pin to the pivot of the tongue. This type of motion increaser has the advantage, aside from simplicity, of providing that the initial motion of the apron is approximately a direct movement in line with the thrust pin movement, which takes

the task of overcoming the inertia and friction opposing the initial movement. The added swinging movement can then be accomplished without exceptional power.

As already noted, the invention may be applied to any other type of push pin operation and is not limited to the particular one described in order to give an example of the invention.

Having thus described my invention, what I claim as new and desire to secure by Letters Patent is:

1. In combination a tool box, an apron pivotally secured at its upper end thereto, a push pin passing through the tool box where the apron lies thereon, and a motion increaser secured to the tool box between said tool box and apron, engaged by the push pin, and engaging the apron, said motion increaser comprising a lever fulcrumed on the tool box.

2. The combination of claim 1 in which the apron is provided with a clearance cavity for the lever.

3. In combination with a slide member mounted on the saddle of a planer having an elevating screw, and a rock plate located on said slide, and power means straddling the elevating screw and engaging the rock plate, a push pin located in the slide and spring held in contact with the rock plate, a tool box mounted on the slide, having on its outer face a lever fulcrumed thereon in a position to be engaged by the push pin, and an apron pivotally held on the tool box and arranged to engage said lever, for the purpose described.

4. The combination of claim 1 in which the apron is spring counterweighted toward movement away from contact with the tool box.

5. In combination a tool box, an apron hinged thereto, a push pin passing therethrough, an oppositely hinged lever mounted on the tool box so as to be engaged by said pin and lying between the tool box and said apron, the distance from the hinge point to the end of the lever being substantially greater than the distance from the hinge point to the location of the tool pin, whereby a motion increaser is supplied to move the apron on its hinged connection a distance further than the motion of the push pin.

6. The combination of claim 5 in which the apron is counterweighted on its hinged mounting.

7. The combination of claim 5 in which the apron is formed with a cavity for clearance of the lever.

8. The combination of claim 5 in which the apron when closed against the tool box has a projection which underlies a shoulder on the tool box in which the apron is counterweighted on its hinged mounting, and in which the lever is mounted on the face of the tool box, said apron being formed with a cavity to clear the lever and its mounting.
